UNITED STATES PATENT OFFICE.

LORENZO D. CORSER, OF EBENSBURG, PENNSYLVANIA.

LEVELING ATTACHMENT FOR HARROWS.

SPECIFICATION forming part of Letters Patent No. 448,502, dated March 17, 1891.

Application filed September 10, 1890. Serial No. 364,554. (No model.)

To all whom it may concern:

Be it known that I, LORENZO D. CORSER, of Ebensburg, in the county of Cambria and State of Pennsylvania, have invented a new 5 and useful Leveling Attachment for Harrows, of which the following is a full, clear, and exact description.

This invention relates to an improved appliance to be used in connection with a harrow, and has for its objects to provide an auxiliary device which will be capable of adjustment with regard to the ground surface it engages, and that will level all inequalities which may exist after the harrow-teeth have 15 operated on the plowed ground, and thus afford a more perfect result, the depth of toothed engagement of the harrow with the soil being also controlled by improved means.

To these ends my invention consists in the 20 construction and combination of parts as is hereinafter described, and pointed out in the claims.

Reference is to be made to the accompanying drawings, forming a portion of this specification, in which similar letters and numbers of reference indicate corresponding parts in 25 all the figures.

Figure 1 is a plan view of a harrow-frame and the leveling attachment with its connections thereon. Fig. 2 is a side elevation in section, taken on the line xx in Fig. 1. Fig. 3 is a detached and enlarged perspective view of a rocking bracket-frame which supports a caster-wheel on the forward end of the 35 harrow-frame. Fig. 4 is a view of the forward caster-wheel and its forked supporting-standard, and Fig. 5 is a face view of a lever which connects the caster-wheel standard with draft devices for the harrow.

The harrow-frame A is preferably made in 40 triangular form of wood or metal, and consists of a center beam 1, joined at the forward end by equally-divergent side beams 2, which are bolted together laterally, as at a , and are 45 similarly connected to a transverse brace 3, which is located at a proper distance in advance of the terminal rear ends of the side and center beams of the harrow-frame.

Preferably the harrow-frame A is furnished 50 with teeth b of a shoveling-blade form, which teeth are arranged in series on the beams 1, 2, and, if desired, on the transverse brace 3

also, to agitate the soil, the depth of engagement of the teeth with plowed ground being regulated by means which will be described. 55

Upon the rear end portions of the center and side beams 1 and 2 a rock-shaft 4 is supported by its journaled body and ends in the boxes c , which shaft is provided with two cranks d , that are located one near each end 60 of the rock-shaft, having equal throw and located in the same plane, projecting from the same side of the shaft 4, preferably toward the front end of the machine. (See Fig. 1.) Two wheels 5 of an equal diameter are journaled on the pins e of the cranks d .

Upon the side beams 2 of the harrow-frame, near the brace 3, two similar bracket-frames 6 are erected. These each consist of two limbs g g' , that are joined at their upper ends. 70 One of the limbs g of each bracket-frame is attached at g^2 to the side beam it rests upon and is rearwardly inclined to produce a stay-brace for the other limb g' , these latter-named limbs being curved to produce forwardly-bent 75 guides, whereon stout spiral springs h are placed. There are a series of equally-spaced tooth-bars i loosely mounted to rock upon the shaft 4, as at i' , the lower portions of which are adapted to engage the soil, and to this end 80 are curved so as to present their lower ends at a proper angle to the ground surface when adjusted to enter the same. The portions of the tooth-bars i that extend above the rock-shaft 4 are forwardly and upwardly projected, 85 having engagement at their upper terminals with the cross-bar 7, which serves as a head-piece to support the series of tooth-bars and rock them simultaneously upon the rock-shaft 4 and for convenience will be so designated. 90

Each end of the head-piece 7 is loosely connected with the guide-limbs g' of the bracket-frames 6 by the encircling staples k or other similar means, which staples embrace the guide-limbs and rest upon the springs h , that 95 normally retain the head-piece 7 elevated and the curved lower portions of the tooth-bars i depressed, as shown in Fig. 2, the strength of the springs h being sufficient to cause the lower ends of the tooth-bars to enter the soil 100 a proper depth for its stirring agitation.

As it is desirable to remove the tooth-bars i from contact with the ground when the device is being transferred from its place of

storage to the locality where it is to be used, there is a lever 8 provided for this purpose, which lever is pivoted on the head piece 7 at k' and projects forwardly a suitable distance, so that the driver may reach its forward end from the seat 9, which is located on the center beam 1 between the cross-brace 3 and the forward end of the harrow-frame A. Upon the cross-brace 3 a spring-latch m or its equivalent is erected, which will engage the top edge of the lever 8 with its hook-nose formed on the side of the free upper end, whereby the lever will be removably secured in a depressed position at this point, the springs h yielding to permit such an adjustment of parts. The rear end of the lever 8 is bent downward sufficiently to freely engage the rock-shaft 4 with its forked lower end k^2 , so that the depression of the forward end of the lever, as stated, will depress the head-piece and rock the tooth-bars i mounted on it.

On the front end of the center beam 1, that is preferably extended for the purpose, a rocking bracket-frame 10 is pivotally attached. Said bracket-frame consists of a single piece of metal, which may be cast or forged into form, the preferred shape being shown in Fig. 3.

As represented, the bracket-frame mentioned is comprised of a rectangular loop-bar n , open at the bottom, the side limbs of which loop loosely embrace the opposite sides of the beam 1. On the forward edge of the loop-bar n two forwardly-curved integral parallel bars n' are projected, which latter are sufficiently separated for their use, and on their front faces, at the center of each curved bar, an integral lug n^2 is formed, these lugs having vertical and aligning perforations produced in them, as at n^3 in Fig. 3.

The bracket-frame 10 is pivoted to the beam 1 at n^4 , near the lower ends of the loop-bar n , and near the upper corner of said bar n^4 a connecting-rod 11 is loosely secured to vibrate the bracket-frame on the pivot-bolt named. A caster-wheel 12 of a proper diameter and width of face is provided; also, a standard 13, which latter is bifurcated to loosely receive the caster-wheel, that is revolvably secured between the limbs of the standard by a cross-bolt o . Above the caster-wheel the body of the standard 13 is formed to loosely engage the perforations n^3 of the ears n^2 , the lower ear resting on the collar o' of the standard. Between the ears n^2 there is a draft-bar 14, mounted on the body of the standard 13, a squared portion o^2 thereon being fitted to a square hole o^3 in the end of the draft-bar, so that a lateral swinging movement of the latter will correspondingly move the caster-wheel 11. When the standard 12 is in place and the other attachments connected to it, all may be revolvably retained on the bracket-frame 9 by a nut on the upper end o^4 of the standard, as shown in Fig. 2.

The rear end of the connecting-rod 11 is

jointed to an upright handle-bar 15, which is loosely secured at its lower end p to the side of the center beam 1. Said handle-bar, which is thus adapted to be vibrated toward the front or rear end of the beam 1, is furnished with an adjustable slide-bolt p' , (shown in dotted lines in Fig. 2,) the lower end of which may be made to interlock with any of the notches q' in the curved rack q . 75

An upright rock-arm 16 is secured firmly at its lower end upon the rock-shaft 4, and to the upper end r of said rock-arm the elongated link-bar 17 is loosely secured, the other end portion r' of which link-bar is forwardly extended of a proper length to have a pivotal connection with the upright handle-bar 15 above the rod 11, as shown in Fig. 2, the link-bar being broken in said figure to avoid interference with other parts it would obscure. 85

The relative arrangement of parts should be such that the caster-wheel 12 and rear wheels 5 will retain the harrow-frame A in or near a horizontal plane when the harrow and its rearward attachment are in service, as 90 shown in Fig. 2.

Should it be desired to deepen the draft of the harrow-teeth b and tooth-bars i , the rearward adjustment of the handle-bar 15 will effect this, and a forward movement of the same 95 bar will rock the caster-wheel 12 rearwardly and downwardly, and the rear wheels 5 will receive a similar adjustment, which will elevate the harrow-frame A and diminish the depth of tooth-draft for the harrow and leveling attachment at its rear.

When the tooth-bars i are in contact with the harrowed ground, they reduce such lumps and slight unevenness of surface as is left by the action of the colter or shovel-teeth b , 105 that are preferably used on the harrow-frame A, so that the work is completed by one operation without requiring the ground to be cross-harrowed.

It will be evident that from the peculiar 110 construction of the supports for the caster-wheel 12 said wheel can be changed in the direction of its progressive movement by the lateral movement of the draft-animals that are attached to the draft-bar 13.

When the machine is moved to or from the place of service over roads or grounds that are not to be harrowed, the wheels are all lowered, so as to raise the harrow-teeth from the ground, and the lever 8 is depressed and secured, as has been explained, which will raise the lower ends of the tooth-bars i a proper distance to avoid ordinary obstructions. 115

Having thus described my invention, I claim as new and desire to secure by Letters 125 Patent--

1. A harrow comprising a triangular frame having blades or teeth along its side bars, front and rear supporting-wheels, a transverse series of teeth extending across the rear end 130 of the frame, each tooth being pivoted between its ends to swing vertically, a head to

which the upper ends of said teeth are connected, and springs pressing the said head upward and thereby forming cushions therefor, substantially as set forth.

5 2. A harrow having a transverse series of teeth extending across the rear end of its frame, each tooth being pivoted between its ends to swing vertically, a head connecting the upper ends of the said teeth, and springs 10 pressing the head upward and forming cushions therefor, substantially as set forth.

3. A harrow having a transverse series of teeth across its rear end, the teeth being all mounted between their ends on a common 15 axis to swing vertically, a head connecting the upper ends of all of the teeth, springs pressing the head upward and forming cushions, a lever having its outer end fulcrumed on the axis of the teeth, pivoted between its 20 ends to the said head, and extending at its inner end toward the center of the frame, and

a catch for retaining the lever depressed, substantially as set forth.

4. The rectangular open frame n , having the two transverse curved parallel bars n' , 25 each provided with a forward-projecting apertured lug n^2 , substantially as set forth.

5. The combination, with the open frame n , having two transverse curved parallel bars n' , each provided with a forward-projecting 30 apertured lug n^2 , of the caster-wheel having a fork 13, provided with a vertical shank passed through the apertures in said lugs and having a squared portion o^2 between said lugs, a shoulder or collar o' below the lugs, a retaining-nut above the lugs, and the forward-projecting piece 14, apertured to fit the squared portion o^2 , substantially as set forth.

LORÉNZO D. CORSER.
